Inventor

UNITED STATES PATENT OFFICE.

WILLIAM A. KEYS, OF NEW YORK, N. Y., ASSIGNEE TO SLIP SCARF COMPANY, A CORPORATION OF NEW YORK.

NECKWEAR.

1,122,946.

Specification of Letters Patent. Patented Dec. 29, 1914.

Application filed January 30, 1909. Serial No. 413,336.

To all whom it may concern:

Be it known that I, WILLIAM A. KEYS, a citizen of the United States, and a resident of the city, county, and State of New York, have invented new and useful Improvements in Neckwear, of which the following is a specification.

My invention relates to neckwear and is particularly adapted to neckwear worn with what is known as two-fold collars, or otherwise called turn-down collars.

The object of my invention is to make neckwear so as to overcome the difficulty with which they are adjusted, while being tied or after being tied, when used between the folds of collars of the kind referred to.

In wearing two-fold collars, it is well known that when the necktie is between the folds of the collar it is very difficult—sometimes almost impossible—to adjust the tie to the right or the left owing to the small space between the folds of the collar into which the neckband of the tie lies. This I have sought to overcome in my invention.

In the drawings, Figure 1 shows a plan view of the necktie embodying the preferred form of my invention; In Fig. 2 I have shown a cross-section taken through Fig. 1 applied to a necktie having a single interlining in the tying ends; In Fig. 3 I have shown my invention applied to a necktie having two interlinings in the tying ends; Figs. 4 and 5 are modifications of my invention.

In the drawings in which similar letters refer to similar parts, A—A are the tying ends of a four-in-hand tie, although my invention is adapted to any other form of necktie.

B is a single ply of material, preferably finished and smooth on both sides, of sufficient strength, which I insert between the

folds of the material A'—A² of the tie and secure same therein by suitable stitching D.

I have shown in cross-section Figs. 2 and 3 a suitable piece of material B inserted in ties having one or two pieces of interlinings respectively and held therein by stitching D.

In Fig. 4 I have shown the strip or bridge B as integral with a portion of the cover fabric A' of the tying ends. Of course, it is immaterial whether it is integral with the cover fabric of the outer face or the inner face of the tie.

In use it will be found that a tie embodying my invention can be readily adjusted as the tie is thinner in that portion which lies between the folds of the rear part of the collar at which point there is the least space for the tie.

Modifications and changes may be made without departing from the spirit of my invention.

What I claim as new and desire to secure by Letters Patent, is:

In a necktie, the combination of a neckband and two tying ends, an intermediate portion of said necktie consisting of a single ply of relatively strong fabric equal in width to the adjacent portions of the necktie, the tying ends formed of several plies, interlinings in said tying ends and rows of stitches extending cross-wise of said tie engaging with the outer plies of the tying ends, the interlinings of the tying ends and the ends of the intermediate portion of the tie, substantially as set forth.

In testimony whereof, I have signed my name to this specification, in the presence of two subscribing witnesses.

WILLIAM A. KEYS.
